APPARATUS FOR THE TREATMENT OF
GASES OR VAPORS WITH LIQUIDSHenry Sharrock Sayles, Norton-on-Tees, Eng-
land, assignor to Imperial Chemical Industries
Limited, a corporation of Great BritainApplication October 1, 1934, Serial No. 746,463

5 Claims. (Cl. 261—112)

This invention relates to apparatus in which gases or vapors are passed into contact with liquid films flowing over packing composed of a plurality of vertical sheet elements arranged 5 transversely in superimposed tiers, such for example, as in gas washing for the removal of solid matter and/or undesired gaseous constituents, the absorption of gases in liquids, the cooling of liquids, distillation, rectification, or chemical 10 reactions in which intimate contact between gaseous and liquid reactants is desirable.

In such apparatus it is important that substantially the whole of the liquid should flow down the surface of the packing in film formation since the free fall of liquid between the 15 elements, hereinafter referred to as cascading, results in a serious loss of efficiency.

According to the present invention, apparatus of the kind described includes means for delivering liquid in film formation to the packing elements, comprising collectors consisting of two or more closely adjoining files or rows of parallel inclined sheets arranged one behind the other, adjacent rows being inclined in opposite directions and adjacent sheets in each row being inclined to such an extent that there is no vertical passage between them, so that liquid delivered from above the said collectors is distributed over both sides of the subjacent packing elements 25 without appreciable cascading and without substantially restricting the flow of gas or vapor.

The collector sheets may be used in conjunction with any approved form of distributor to deliver the liquid on to the uppermost tier of the packing, the sheets being inclined to such an extent that there is no vertical passage between adjacent sheets in each row. The lowermost edges of the sheets must be so placed relative to the uppermost tier of the packing elements 40 that the liquid falling from the collector sheets is directed on to the surface of the packing; thus the lowermost edges of the sheets may touch the top of the packing elements, or if desired the sheets may be made integral therewith. It is important that the rows of sheets should adjoin as closely as possible since otherwise the gaps would permit a free fall of liquid through the packing.

The packing may be composed of a plurality of vertical metal sheet elements arranged transversely in superposed tiers, and each tier may interlock with adjacent tiers by means of slits in the component vertical sheets, the whole or part of the tongues formed by the slits at the top of 55 each of the sheets forming each tier being in-

clined alternately in opposite directions to form collector sheets.

The width of the collector sheets is preferably small compared with the width of the subjacent packing elements to which they deliver liquid, 5 so that the liquid is distributed substantially uniformly over both sides of the said packing elements. Collector sheets may be provided at the top of each tier of packing elements, and this is especially advantageous when high rates of 10 liquid flow are used, since otherwise the liquid is liable to cascade instead of flowing from tier to tier in film formation.

The invention is illustrated in the accompanying drawings in which:

Fig. 1 is an elevation of several tiers of packing elements and collectors embodying this invention.

Fig. 2 is a perspective view of portions of three of the packing elements and collectors belonging to three separate tiers of the elements shown in Fig. 1.

Fig. 3 is a perspective view of a modified form of the invention, and

Figs. 4 and 5 are end elevations or profile views of modified forms of collectors.

Referring to the drawings, more particularly to Figs. 1 and 2, the packing comprises a number of vertically disposed rectangular plane sheet elements 1 of suitable metal, such as aluminum, 30 arranged in superposed tiers, the elements in each tier being substantially parallel to one another and arranged in contact with and transversely to those in the next tier, said elements being provided with equally spaced slots 2 along 35 their upper and lower edges.

As has been previously emphasized, an important feature of this invention resides in the provision of means for delivering liquid in film formation to the packing elements in such a way 40 that cascading is minimized and maximum efficiency is attained without substantial restriction of the flow of gas or vapor. In the present instance, such liquid delivery means comprise collectors or collecting plates or sheets 3, which 45 receive the liquid, preferably from a liquid distributor, not shown, and deliver it to the packing elements 1. In the example illustrated, collectors 3 are formed from tongues of metal formed by the slots 2 in the upper edge of each packing element 1, the tongues being bent alternately in opposite directions and to such a degree that their uppermost edges 4 lie over the vertical subadjacent elements of the packing when the packing is assembled by interlocking the slots 2 55

in the upper edges of the elements 1 in one tier with the slots 2 in the lower edges of the elements in another tier. Thus a plurality of closely adjoining rows or files of substantially parallel inclined collector sheets 3 are provided, adjacent rows being inclined in opposite directions and in such a way that the vertical passages between the packing elements are substantially completely masked, so that liquid delivered from above the said collector sheets is distributed in film formation over both sides of the subadjacent packing elements without appreciable cascading and without substantially restricting the flow of gas or vapor. In the example illustrated, the collector plates 3 are made integral with the packing elements 1, but they can be made separately and when so made, the lowermost edges of the collector sheets may touch the top of the packing elements, but in any event the lowermost edges of the collector sheets must be so placed relative to the uppermost edges of the packing elements that the liquid falling from the collector sheets is directed on to the surface of the packing.

The tongues or collector sheets 3 are inclined alternately in opposite directions and the width of said collector sheets is preferably small compared to the width of the subadjacent packing elements to which they deliver liquid because this results in the liquid being distributed substantially uniformly over both sides of said packing elements.

In Figs. 1 and 2, collector sheets 3 are provided at the top of each tier of packing elements and this arrangement has certain definite advantages, but it is not necessary within the broad scope of the invention and the collectors can be eliminated from the packing elements in the tiers below the uppermost, as in Fig. 3. In Fig. 3 the packing elements 1^a and 1^b are plain, the elements in the upper tier resting on or being in contact with the transversely arranged elements of the subadjacent tier, there being no interlocking of the elements in the two tiers. The collector sheets 3^b of Fig. 3 are inclined alternately in opposite directions and small in width as compared to the width of the subadjacent packing elements 1^b, as in Figs. 1 and 2.

In Figs. 1-3 inclusive, the collector sheets are plane in cross-section or profile, but it is obvious that these collectors may have various

profiles, two examples of which are illustrated in Figs. 4 and 5, Fig. 4 showing curved or convex collector sheets 3^c and Fig. 5 showing oppositely curved or concave collector sheets 3^d, it being understood that the lower edges of these collector sheets direct liquid to the upper edges of subadjacent packing elements.

It is to be understood that the invention is not limited to the exact construction and arrangements shown and described and that various modifications can be made without departing from the spirit and scope of the invention as defined in the appended claims.

What is claimed is:—

1. Apparatus for treating gases or vapors with liquids, comprising a packing composed of a plurality of vertical sheet elements arranged transversely in superposed tiers, and means for delivering liquid in film formation to said elements comprising collectors consisting of two or more closely adjoining rows of parallel inclined sheets, adjacent rows being inclined in opposite directions and adjacent sheets in each row being inclined to such an extent that there is no vertical passage between them, the bottom edges of the collector sheets being substantially parallel to the top edges of the subadjacent packing elements so that liquid delivered from above the said collectors is distributed over both sides of the subjacent packing elements without appreciable cascading and without substantially restricting the flow of gas or vapor.

2. Apparatus as claimed in claim 1, in which the width of the collector sheets is small compared with the width of the subjacent packing elements to which they deliver liquid so that the liquid is distributed substantially uniformly over both sides of the said packing elements.

3. Apparatus as claimed in claim 1, in which collector sheets are provided at the top of each tier of packing elements.

4. Apparatus as claimed in claim 1, in which the collector sheets are integral with the packing elements.

5. Apparatus as claimed in claim 1, in which the packing elements interlock by means of slits and the tongues thus formed are bent alternately in opposite directions to form the collector sheets.
